(57) CLAIM

The ornamental design for a table, as shown and described.

DESCRIPTION

FIG. 1 is a front perspective view of a table according to a first embodiment of the new design;

FIG. 2 is a rear perspective view thereof;

FIG. 3 is a front view thereof, the rear view being identical to the front view;

FIG. 4 is a right side view thereof, the left side view being identical to the right side view;

FIG. 5 is a top view thereof; and,

FIG. 6 is a bottom view thereof.

The broken lines in the drawings illustrate portions of the table which form no part of the claimed design.

1 Claim, 6 Drawing Sheets
